UNITED STATES PATENT OFFICE

FORREST A. WALKER, OF SYRACUSE, NEW YORK, ASSIGNOR TO WALKER DISHWASHER CORPORATION, OF CHICAGO, ILLINOIS, A CORPORATION OF DELAWARE

MECHANICAL DISHWASHER

Application filed July 24, 1926. Serial No. 124,640.

This invention relates to a mechanical dish washing machine of the type in which the dishes and other utensils to be washed are supported in an open-work tray or trays within a suitable vat containing a limited quantity of water which is forced or impelled upwardly through open-work trays or carriers and against the dishes and other utensils with a whirling centrifugal motion in such manner as to impinge against the dishes with a glancing or diagonal impact due to the construction of the impeller and to the position of the dishes relatively to the direction of motion of the water.

15 This operation is continued until the dishes are thoroughly cleansed following which the impeller may be stopped temporarily to allow the foul water to be drawn off and rinsing water introduced and circulated in the same manner for final cleansing purposes after which the rinsing water may be drawn off and the dishes and other utensils allowed to dry in the carriers either before or after removal from the vat.

20 In machines of this type the impeller is rotated in a plane close to the conical bottom of the vat and is driven by an upright shaft extending through the apex of said bottom and thus co-axial with the axis of the vat, the shaft being preferably driven by an electric motor mounted upon the frame of the machine.

The present machine is adapted to be supported mainly upon the side wall of a room or equivalent upright support thereby obviating the use of the usual portable supporting frame in which case it is desirable to hang the motor directly upon the underside of the vat and preferably at the rear or wall side 35 of the axis of said vat so as to leave clear floor space around the remaining sides.

This manner of supporting the motor together with the extra load of the driving connections between the motor and impeller shaft and the downward thrust of the impeller due to the upward lift of the water by the impeller throws an excess load upon the connections between the vat and supporting wall.

40 One of the objects of the invention is to

55 relieve those connections from excess load and end-thrust strains and at the same time to steady the entire machine from undue vibration by providing a supporting leg co-axial with the axis of the vat and impeller shaft so as to better resist the downward thrust of the impeller shaft and also to partially support the motor and vat.

Another object is to make the leg in sections adjustable one upon the other to assure 60 its contact with the floor when the vat is attached to the wall and to assure the engagement of the lower end-thrust bearing with the lower end of the impeller shaft.

A further object is to mount the leg and 65 motor upon a supplemental frame or casing and to provide simple means for connecting the casing to the underside of the vat so that the motor, gear case and leg may be removed or replaced as a unit.

70 A further object is to provide the casing with a post extending through the apex of the bottom of the vat and above the water level for receiving the impeller shaft and forming a water tight connection between 75 said shaft and impeller.

75 Other objects and uses relating to specific parts of the machine will be brought out in the description.

In the drawings:—

80 Figure 1 is a perspective view of a dishwashing machine embodying the various features of my invention.

85 Figures 2 and 3 are respectively a top plan and a front elevation of the same machine.

90 Figures 4 and 5 are enlarged transverse vertical sectional views taken respectively on lines 4—4, and 5—5, Figure 2.

Figure 6 is a detail vertical section of the water-level regulator and indicator together with the valve operating means for controlling the drainage outlet taken on line 6—6, Figure 2.

95 Figure 7 is an enlarged horizontal sectional view taken in the plane of line 7—7, Figure 6.

Figure 8 is an enlarged detail sectional view taken on line 8—8, Figure 2.

100 Figure 9 is a transverse vertical sectional view taken in the plane of line 9—9, Figure 8.

As illustrated, the frame of the machine

comprises a substantially rectangular cap or top section —1— forming the top of a circular vat —2— and provided with inner and outer marginal flanges —3— and —4— united by an intermediate roll at the top.

5 This cap or top portion —1— is provided with a central relatively large circular opening —5— and an inwardly projecting horizontal ledge —6— surrounding the opening for receiving and supporting a lid or cover —7— and an upper tray or basket —8—, said opening being of sufficient size to permit the passage thereto of the basket —8— and additional tray or basket —9—.

15 The lower face of the ledge —6— is rabbed throughout its length for receiving the upper end of the vat —2— which is clamped to the underside of the cap section —1— by bolts —10—, the latter being arranged in 20 spaced relation circumferentially around the marginal edges of the upper end of the vat.

25 These bolts are preferably hinged to apertured lugs —11— on the underside of the top section —1— and are movable in slotted lugs —12— on the upper end of the vat to facilitate the assembling of the parts —1— and —2—, one upon the other.

30 The flange —4— at the rear side of the top section —1— is provided with vertical slots —13— opening from the bottom upwardly for receiving L-shaped bolts or screws —14— which are adapted to be screwed into the side wall as —A— of a room or to any other suitable upright standard, the inner 35 ends of the screws or bolts —14— being preferably turned upwardly to enable the rear flange to be engaged therewith by a downward movement or removed therefrom by upward displacement.

40 The cap or top section —1— is therefore supported at its rear side directly upon the wall —A— while the vat —2— is supported at its upper end entirely by the top —1— through the medium of the bolts —10— and 45 when placed in operative position projects some distance above the lower edge of the marginal flange —4— so that the joint between the two sections will be concealed by said flanges.

50 The lid or cover —7— is made in the form of a shallow inverted cup which is circular in plan and of slightly less diameter than the interior diameter of the annular flange —3— so as to rest upon the upper face of 55 the ledge —6—.

The vertical depth of the cover is slightly less than the corresponding depth of the flange —3— above the ledge —6— and is provided with a substantially flat upper face 60 which, when the lid is closed lies in a horizontal plane slightly below the upper edge of the cap section —1— to be used when closed for supporting various articles and also to prevent the upward displacement of 65 the washing fluid when circulated in the

vat by the impeller mechanism, presently described.

The rear side of the cover —7— is provided with hinge sections —15— which are pivoted at —16— to suitable lugs on the adjacent portions of the top section —1— to permit the lid to be swung from a closed horizontal position upwardly and rearwardly beyond a vertical position or against the inner face of the wall —A—.

70 The main body of the vat —2— is slightly tapered downwardly and is provided with an inverted conical bottom —17— having an opening in its apex for receiving a bushing —18—, a post —19— and an impeller shaft —20—, the upper end of the bushing —18— is enlarged and engaged with the upper face of the adjacent portion of the bottom —17— to form a water-tight joint therewith, said bushing being extended downwardly some distance below the bottom and threaded externally for receiving a nut —21— which, together with the bushing and suitable packing —22—, constitutes a gland for the reception of the post —19—.

75 This post extends through and some distance above and below the bushing —18— and preferably above the level in the vat as regulated by an overflow hereinafter described.

80 A combined gear-case and motor support constituting a supporting frame 23 for the power-unit extends across the under side of the bottom of the vat —2— from the axis toward the rear side thereof and has its rear end attached to the underside of the overlying portion of the vat by means of a strap —24— and bolts —25—.

85 The front end of the casing —23— extends under the apex of the bottom —17— and is provided with a gear chamber —26— for receiving a gear —27— which is secured to the lower end of the upright impeller shaft —20—.

90 The lower end of the tubular post —19— extends into an opening —28— in the top wall of the gear chamber —26— while the shaft —20— extends through and some distance below the tubular post —19— and has its lower end seated on an end-thrust bearing —29— in the bottom wall of the gear chamber —26—, said bearing —29— being seated in the lower end of a socket —30— which receives the lower end of the shaft —20— and holds the latter against lateral movement.

95 The bottom wall of the gear chamber —26— is made separate from the top wall to permit access to the gear and is secured thereto by screws or bolts —31—, Figure 4, to firmly hold those parts in fixed relation to each other when adjusted for use.

100 The front end of the casing —23— is supported by a sectional leg —32— consisting of an upper tubular section —33— and a

lower section —34—, the section —33— being threaded internally while the section —34— is threaded externally for engaging the internal threads and permitting the 5 length of the leg to be adjusted as may be required for properly supporting the inner end of the casing —23—.

The leg —32— is co-axial with the axis of the vat —2—, the post —19— and shaft 10 —20— and serves not only to partially support the vat through the medium of the casing —23— and connection —24— and also through the medium of the post —19— but also serves to resist the downward thrust of 15 the impeller shaft —20— through the end-thrust bearing —29— due to the lifting action of the impeller upon the water.

The shaft —20— extends upwardly above the upper end of the tubular post —19— and 20 is threaded at its upper end for receiving and supporting an impeller —35—.

This impeller is provided with a central hub open at the bottom and closed at the top which latter is provided with a threaded 25 socket engaged by the upper threaded end of the shaft —20— for transmitting rotary motion from the shaft to the impeller.

The impeller is provided with opposite 30 wings or vanes —36—, the lower edges of which travel in close proximity to the upper surface of the conical bottom —17—, said blades being provided with baffles —37— projecting in the direction of rotation to limit the centrifugal throw of the water as the 35 impeller is revolved and also to assist in deflecting the water upwardly through the trays —9— and —8— and against any dishes or utensils which may be supported in the trays, the tray —9— being supported upon the 40 outer marginal edge of the inclined bottom —17— as shown more clearly in Figure 4.

Drainage and overflow

A pipe —38— is connected to the interior 45 of one side of the apex of the conical bottom —17— to extend laterally and downwardly therefrom and has its outer end connected to one side of an overflow regulator —39—, the latter having its other side connected to 50 a drain pipe —40—, Figure 5.

This regulator is provided with an upright 55 partition —41— dividing it into opposite upright chambers —42— and —43—, said partition having an opening —44— at about the level of the upper end of the conical bottom —17— for extending said chambers —42— and —43— and allowing the liquid to overflow from the chamber —42— into the chamber —43— and thence into the drain 60 pipe —40— for maintaining a pre-determined level of the washing fluid in the bottom of the vat —2—.

The pipes —38— and —40— are arranged 65 nearly in alinement with each other while the partition —39— is provided with an addi-

tional opening —45— in alinement with the pipes —38— and —40—, said additional opening —45— being controlled by a valve —46— which is operable at will.

A valve operating rod —47—, Figure 6, is 70 connected at its lower end to the valve supporting lever —48—, Figure 7, and has its upper end extended through an opening —49— in an insert —50— in the top section —1— for receiving an operating handle 75 —51— whereby the valve may be controlled from the top of the machine.

Water level indicator

A float —52— is supported on the lower 80 end of a stem —53— within the chamber —42— of the level regulator —39—, the upper end of said rod being extended into a sight tube —54— in the top section —1— so that when the valve —46— is closed the water 85 rising in the vat —2— will take the same level in the chamber —42— thereby lifting the float —52— and rod —53— and permitting the water-level to be indicated by the relative position of the upper end of the rod 90 —53— in the sight tube —54—.

Water supply

A spray nozzle —55— is secured in one 95 side of the vat —2— some distance above the normal level of the lower tray —9— for receiving water from a supply pipe —56— through the medium of a controlling valve —57— which together with the nozzle —55— are located below the top section —1—, said 100 valve having a stem —58— projecting through a bushing —59— in the top section —1— and having its upper end provided with a handle —60— by which the valve may be operated to regulate the flow of water into 105 the vat for washing or for rinsing purposes.

Power means

An electric motor —61— is secured by bolts 110 —62— to the underside of the rear portion of the casing —23— and preferably directly below the connecting strap —24—, said motor having its armature shaft —63— provided with a worm —64— meshing with the gear —27— for transmitting rotary motion 115 to the impeller shaft —20—.

The bottom section of the gear chamber —26— is somewhat tapered while the upper section —33— of the leg —32— is hollow and adapted to receive the apex of the bottom section of the gear chamber and to abut against the same whereby, when the lower section —34— is adjusted to contact with the floor, the upper section may be adjusted to firmly engage and support the lower section of the gear chamber and thereby to partially support the bracket —23— and vat —2— in 120 addition to its other function of resisting the downward thrust of the impeller shaft —20— particularly when the impeller is in 125 130

action for lifting and circulating the water circumferentially by centrifugal force within the vat —2— and against any dishes or utensils which may be supported in one or both of the trays —9— and —8— or in a supplemental tray —9'— which is carried by the tray —9—.

The current supply wires as —61'— leading from any available source of current supply are carried through a conduit —65—, Figure 8, which is supported by brackets —66— within the marginal roll of the cap section —1— along one side thereof as indicated by dotted lines in Figure 2, said conduit 10 also serving to receive and support at its front end an electric switch —67— by which the current to the motor may be controlled.

It will be noted from the foregoing description that the positioning of the leg —32— directly under the apex of the bottom of the vat —2— and co-axial with the impeller shaft —20— leaves a clear foot space around the front and sides of the leg below the vat so as to avoid contact of the feet therewith in moving around the machine in addition to its other functions of partially supporting the vat and motive power unit and resisting the downward thrust of said shaft due to the lifting action of the impeller 25 upon the water in impelling the same upwardly and centrifugally with a whirling motion.

It will also be observed that when the lid or cover —7— is closed its upper flat surface together with the upper surface of the surrounding portion of the cap section —1— which is in nearly the same horizontal plane affords a convenient work-table for various 30 uses and that the arrangement of the various controls such as the water supply control and the drainage control together with the water level indicator mainly at the rear of the lid or cover —7— and at the top of the cap section affords a more convenient means for observing and operating those parts than has heretofore been practiced while the general construction of the machine is simple, free from exposed moving parts and may be easily 35 kept in a thoroughly sanitary condition.

Operation

The dishes or other utensils to be washed are usually placed in their respective trays, —9—, —9'— and —8— before the latter are placed in the vat —2— after which these trays or carriers with the dishes therein are placed in operative position within the vat.

The valve —57— is then opened by means 60 of its operating member —60— to allow the water or other washing fluid to pass from the supply pipe —56— through the nozzle —55— and into the vat —2— until it reaches a pre-determined level as regulated by the overflow —44— and indicated by the float actu-

ated indicator —54—, the valve —57— being then closed.

The switch member —67— is then operated to start the motor and thereby to rotate the impeller —36— which forces the washing fluid upwardly and circumferentially with a whirling motion, the centrifugal throw of the fluid being retarded by the fins —37— which cause the washing fluid to be thrown upwardly at different angles in addition to the upward lift of the water by the rotation of the impeller thereby causing a thorough upward agitation of the water against the dishes and other utensils in their respective trays, it being understood that the water which is displaced upwardly returns by gravity to the impeller to be again agitated upwardly and centrifugally thereby causing the water to impinge against the dishes and other utensils with a glancing impact for thorough 75 cleansing the same.

After the dishes are thoroughly cleansed the motor may be temporarily stopped and the valve —46— opened to drain off the impure water whereupon the valve —57— may be again opened to allow fresh water to be sprayed over the dishes and other utensils for rinsing purposes and after the dishes are thoroughly rinsed the valve —57— is again closed and the cleansed and rinsed dishes and other utensils therein are allowed to remain in the vat until thoroughly dried.

The valve —46— may then be closed and the trays and other utensils therein may be removed after opening the cover or lid —7—, the machine being then ready for a repetition of the operation previously described.

It will be noted that the volume of water in the tank for washing purposes is limited by the overflow —44— to a level just sufficient to cover the impeller —36— thereby, not only conserving the water, but also the power required for lifting and circulating the water by the impeller and that this lifting action of the impeller produces a downward thrust upon the shaft —20— which, in turn, is resisted by the end-thrust bearing —29— and transmitted directly to the leg —32— thereby relieving the strain upon the connections between the cap section —1— and the upright wall —A— and also reducing to a minimum the vibration of the machine as a whole incidental to the rotation of the impeller.

What I claim is:

1. In a mechanical dishwasher, a vat, a gear-case arranged under the vat, a tubular post projecting from the gear-case through an opening in the bottom of the vat, an upright impeller-shaft extending through the post and having its lower end journaled in the gear-case, an impeller mounted on the shaft within the vat, and a leg co-axial with the shaft and engaged with the gear-case for 125

supporting the same and for resisting downward thrust of the shaft.

2. In a mechanical dishwasher, a vat having a central opening in its bottom, means for supporting the vat in an upright position, a gear casing beneath the vat in vertical alinement with said opening, a supporting leg for said casing in vertical alinement with said opening and having its upper end engaged directly with said casing, a tubular post secured to said casing and extending upwardly therefrom through said opening and some distance above the bottom of the vat, a rotary shaft having its lower end journaled in the casing and its upper end extended through and above said tubular post, a motor and gears within said casing for transmitting motion from said motor to said shaft.

In witness whereof I have hereunto set
my hand this 20th day of July 1926.

FORREST A. WALKER.
